AERIAL ADVERTISING BANNER

Paul E. Hovgard, Bristol, Pa., assignor to Kellett
 Autogiro Corporation, Philadelphia, Pa., a corporation of Delaware

Application November 22, 1933, Serial No. 699,223

1 Claim. (Cl. 40—127)

My invention relates to new and useful improvements in aerial banners, and it relates more particularly to aerial banners, for use in aerial advertising.

5 The object of my present invention is to facilitate the flying, as well as the take-off of aerial banners, to increase their stability in flight and generally to facilitate their use and operation.

10 With the above and other objects in view, my invention consists of certain novel features of construction which will appear more fully from the following detailed description.

15 For the purpose of illustrating my invention, I have shown in the accompanying drawings forms thereof which are at present preferred by me, since the same have been found in practice to give satisfactory and reliable results, although it is to be understood that the various instrumentalities of which my invention consists can be 20 variously arranged and organized and that my invention is not limited to the precise arrangement and organization of the instrumentalities as herein shown and described.

25 Referring to the drawings, in which like reference characters indicate like parts,

Figure 1 represents a schematic side-elevational view of a banner embodying my invention;

Figure 2 represents a schematic side-elevational view showing another banner embodying 30 a modified form of my invention.

Figure 3 represents a section on line 3—3 of Figure 2.

Figure 4 represents a fragmentary side-elevational view of the trailing end of a banner showing a variable tail-resistance member embodying my invention, the latter being shown in the take-off condition;

Figure 5 represents a similar view, shown in the flight condition;

40 Figure 6 represents a side-elevational view, on a much enlarged scale, of the release mechanism for changing the resistance member from its take-off condition to its flight condition.

45 In each of the embodiments of my invention shown in Figures 1, 2 and 4, I form a banner of a series of spreader bars 10, spaced suitable distances from each other and connected by longitudinal stringers 11 in a manner similar to that disclosed in the Dupont Patent No. 1,901,855, or 50 in the copending applications Serial Numbers 673,083 and 686,504.

55 The construction of the banner and the details of its various parts may be of any of the forms disclosed in said Dupont patent and in said co-pending applications, the present invention re-

lating more particularly to the leading edge of banners of any of these types disclosed in said Dupont patent and in said copending applications and to the manner in which the stability and correct flight position of the banner is obtained, and further relates (as in Figure 4) to the trailing edge of said banners.

5 In the embodiment of my invention shown in Figures 1 and 2, I provide a leading spreader bar 12 of relatively greater stiffness and cross-sectional area than the spreader bars 10, and having a greater resistance to bending than the subsequent spreader bars 10.

10 The leading spreader bar 12 may be of bamboo or hollow duraluminum tubing, or an equivalent material.

15 In the embodiment of the invention shown in Figure 1, I provide an upper diagonal metallic brace rod 14, and a lower diagonal metallic brace rod 15, having corresponding eyelets at their meeting ends (the eyelets being not shown but being hidden by the metal juncture plate 16). The diagonal rods 14 and 15 are joined by any suitable bolt or fastening means 17 extending through their respective eyelets and extending 20 through the tie-plate 16. The flexible tow-line 18, fastened to the towing craft, is then connected to the plate or plates 16, by means of another 25 bolt 19.

30 The diagonal rods 14 and 15 are connected to the upper and lower ends of the leading spacer bar 12 by means of clamp-members 20 and 21 which include straps embracing the spreader bar and held together by clamp bolts 22 and metallic anchorages 23 projecting from said straps 20 and 21, through which said diagonal rods 14 and 15 are extended. The rods 14 and 15 may be fastened by nuts 24 and 25 threadedly secured to the ends of the rods.

35 The upper diagonal 14 is preferably shorter than the lower diagonal 15, so that the effective towing force is applied above the effective center of the leading spacer bar 12.

40 If desired, a central brace 26 may also be interposed between the outer ends of the diagonals 45 14 and 15 and the leading spreader bar 12. The central brace 26 is preferably made integral with the plates 16 and said plates 16 may thus be related to said brace 26, in the nature of a bifurcated end portion of said brace. The rear end 50 of the brace 26 may also be provided with clamp straps 27, formed of suitable sheet metal and fastened by a clamp bolt 28.

55 In the embodiment of the invention shown in Figure 2, the tow-line 18 is connected directly to 55

the front spreader bar 12, at a point suitably above the center of gravity of the leading edge. In the preferred embodiment I also provide any suitable means whereby the center of gravity of the leading edge of the banner is lowered to a point beneath the center of said leading edge. This may be accomplished by fastening any suitable weight, such as the lead-weight 29 to the lower end of the spreader bar 12. This can be accomplished by means of straps 30 embedded in the lead weight and the clamp screw 31, as shown particularly in Figure 3; (in a manner similar to the manner in which the members 20, 21 and 21 are fastened to the leading spreader bar 12 in Figure 1).

In the embodiment of my invention shown in Figure 2, the towing force is applied approximately at the point or in the zone of the center of drag of the leading edge of the banner, while the center of gravity is positioned somewhat below this center of drag.

By reason of the novel constructions hereinabove described and illustrated in Figures 1 and 2, certain definite advantages are obtainable. Thus, simpler constructions are provided which eliminate flexible bridles and their tendency to tangle or "foul". Moreover, by virtue of either of the foregoing constructions, the banner will become more quickly responsive to sudden changes in the elevation of the towing craft, and will not be subjected to distortion at the front end because in these constructions the tow line is hinged or connected either directly to a rigid bridle as illustrated in Figure 1, or to the banner itself as illustrated in Figure 2. The resultant banner distortion which would be incident to a sudden upward or downward pull upon a flexible bridle may thus be eliminated either by the complete omission of the flexible bridle or by the substitution therefor of a rigid bridle.

In Figures 4, 5 and 6 I have illustrated means whereby the drag imposed upon the trailing end of the banner may be momentarily increased during take-off, thereby to cause the banner to rise into the air more rapidly and to cause the banner to take off from the ground more quickly.

To effect this, I have provided a novel aerodynamic resistance member comprising a wind-sock 33 which may be of any suitable construction, as for instance the form of construction shown in copending application Serial No. 673,083, the leading edge 34 of which is surrounded by a parachute 35 formed of any suitable flexible material, such as silk, canvas or the like. The parachute 35 has a center opening corresponding to the leading edge 34 of the wind-sock 33. The parachute-like member 35 is provided with any suitable number of shroud lines 36, connected to its leading edge 37 and the shroud lines 36 are connected to a common juncture ring 38. The juncture ring 38 in turn is connected through any suitable eyeleted metallic link 39 to a release hook 40 of a release device 41. The release device 41 consists of any suitable plate-like member in which the hook 40 is hinged or pivotally mounted as at 42, and having a slot 43 in which the hook 39 may enter. The release arm 44 of the hook 40 is connected by

any suitable flexible connection, such as rope, cable or the like 45, to the trailing spreader bar 46 of the banner. This may be effected directly or through the intermediate ring 47 and link 48 and anchorage member 49, fastened to the bar 46.

The release device 41 on the other hand, is connected through a helical tension spring 50 to the spreader bar 46. The wind sock 33 is in turn connected through its shroud lines 51 and the line 52, also to the spreader bar 46.

In take-off the banner, the parachute-like member 35 is tied to the release hook 40 in the manner shown in Figure 6, thereby causing the parachute to be maintained in operative relation during take-off. Thus, in taking off, the parachute will be held by the shroud lines 36 and will thus give increased resistance to the trailing end of the banner. As the speed of the banner increases, however, (after taking off) the resistance of the parachute 35 increases, and thus causes a distension of the spring 50. This in turn causes a relative movement of the release unit 41 with respect to the spreader bar 46. Since the length of the release line 45 is fixed, the release arm 44 will be operated and the hook 40 deflected whenever the resistance of the parachute increases sufficiently to stretch the spring 50 to the release point. Once the hook 40 has released the shroud lines 36, the wind carries the parachute-like member 35 backward, until the parachute-like member folds back on the outside of the wind sock 33, thereby lessening the resistance at the trailing end of the banner, as shown particularly in Figure 5.

While in the drawings I have shown the parachute-like unit applied merely to the upper part of the trailing end of the banner, it may also be applied to the lower portion or to the center portion, as may be desired, or it may be applied to both the upper and lower portions.

I am aware that my invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I hereby claim as new and desire to secure by Letters Patent, is:

An aerial display banner, adapted to be towed in a generally vertical plane by a power-driven aircraft, comprising a plurality of longitudinal stringers, rigid frame means including at the rear thereof a spreader spacing said stringers apart at the leading edge of the banner and including rigid rods connected to the ends of the spreader and converging forwardly therefrom and connected together at their converging ends at a point above the center of gravity of the frame, and a tow line connected to the frame at substantially the zone of convergence of said rods, whereby the leading edge of the banner is made more fully responsive to the changes in the relative direction of the tow line.

PAUL E. HOVGARD.
